UNITED STATES PATENT OFFICE.

DOUGLAS CHARLES OWEN, OF HARDENBURG, NEW YORK.

AEROPLANE-LEVEL INDICATOR.

1,277,748.

Specification of Letters Patent. Patented Sept. 3, 1918.

Application filed October 5, 1916. Serial No. 123,925.

To all whom it may concern:

Be it known that I, DOUGLAS C. OWEN, a citizen of the United States, residing at Hardenburg, in the county of Ulster and State of New York, have invented certain new and useful Improvements in Aeroplane-Level Indicators, of which the following is a specification.

This invention has reference, generally, to geometrical instruments; and, the invention relates, more particularly, to a novel means for ascertaining the pitch of aeroplanes when flying.

The invention has for its principal object to provide a device of the character stated, whereby the aviator will be accurately advised of the pitch of the aeroplane, and may definitely ascertain the position assumed by the machine when the same is ascending or descending, consequently allowing the planes to be properly adjusted.

Still further, the invention embodies an improved support for the pitch indicating means, the same being so mounted as to prevent accidental displacement thereof or material undue play.

Other and further improvements and novel details in the construction and arrangement of parts will be appreciated from the description to follow, which for a clear understanding of the invention should be considered in connection with the accompanying drawings, forming a part thereof wherein a preferred embodiment of the invention is shown for the purpose of illustration.

In the drawings:

Figure 1 is a side elevation of my improved device showing part of the same broken away and in sections,

And Fig. 2 is a top plan.

With more particular reference to the drawings, wherein like reference numerals refer to corresponding parts throughout the several views, the device comprises a supporting base indicated in its entirety by the numeral 1, the said base having arranged upon the lowermost portion thereof, an angular flange 2, in which there is arranged a plurality of openings for receiving screws 3, the said screws being embedded within a suitable object or support and the base is thus permanently secured in position. The upper portion of the supporting base 1 is dished to form a concaved seat as indicated by the numeral 4, into which the pitch in-

dicating means, which will be presently described, is placed.

With a view toward providing for means whereby the pitch or angular movement of the aeroplane may be ascertained during the flight thereof, there is provided a hollow spherical body 5, the same being formed of a suitable transparent material, such as glass, or the like. Alcohol, light oil, or other relatively non-expansive fluid is contained within the hollow spherical body 5 and is indicated by the numeral 6. It is evident that the placing of the fluid 6 within the spherical body, may occur during the molding thereof if so desired. A bubble 7 is blown therein and as will be understood, will remain at all times in alinement with the vertical axis of the spherical body. Hence, should the positioning of the supporting base 1 be changed, due to the varied flight of the aeroplane, such movement will cause the tilting of the spherical body 5, the bubble 7 however remaining at all times, in its normal position. In order that the pitch of the spherical body 5 may be correctly ascertained, there is arranged about the said body, a plurality of circumferentially extending graduations, generally indicated by the numeral 8. If desired, designating numerals, designating the numerals of the various graduations may be arranged in proximity thereto. To secure the spherical body 5 within the concaved seat 4, there is arranged thereabout, a screen 9, preferably formed of coarse mesh, the ends thereof, as will be obvious, upon reference to Fig. 1, being connected to the periphery of the supporting base 1 in any suitable manner, such as by soldering, welding, or the like, and thus it will be evident that undue vertical and lateral movement of the spherical body 5 is prevented.

From the foregoing, it will be appreciated that with my improved device arranged upon an aeroplane, should the course thereof be changed, that is, the pitch of the machine varied, the aviator will be accurately advised thereof by merely noting the position of the bubble 7 with relation to the various circumferentially extending graduations 8 and may adjust the planes of the machine accordingly. Furthermore, when ascending or descending, the pitch assumed by the aeroplane may be definitely ascertained and if desired, the planes may be readjusted, just as conditions or preference may dictate,

By placing a non-volatile fluid within the hollow spherical body 5, it is evident that breakage of the same due to expansion is eliminated, furthermore liability of freezing the same, due to the low temperatures to which it will be subjected, will be lessened.

Although I have described my improved device as being particularly adapted for use in conjunction with aeroplanes, it may be 10 here noted that the device may be equally well used upon vehicles, and when so used, will serve in the capacity of the usual goniometer, thereby providing means which will enable the driver of the vehicle to be definitely advised of the pitch of the various 15 grades as traversed by the vehicle.

While I have herein illustrated and described with a considerable degree of particularity, constructural details of the device embodying my invention, it is to be understood that the invention is not limited 20 to the particular form and arrangement of the several parts, which may be modified within a wide range without departing from

the essence of the invention, the construction 25 shown and the description based thereon, being intended to be taken in an illustrative rather than a limiting sense.

I claim:

A level comprising a supporting base, said 30 base having a semi-spherical pocket formed therein to provide a seat, a spherical transparent body receivable within said seat, said body having two sets of crossed circumferentially extending graduations arranged 35 thereon, fluid means contained within said body with an air bubble within said body for indicating the angular movement of said base, and reticulate means engaged around said base and extending over said spherical 40 body for retaining the latter in proper position in said base.

In testimony whereof I affix my signature in presence of two witnesses.

DOUGLAS CHARLES OWEN.
